Primary Examiner—Stella M Reid*Assistant Examiner*—Elizabeth J Oswecki(74) *Attorney, Agent, or Firm*—Gallagher & Dawsey Co., LPA; Michael J. Gallagher; David J. Dawsey(57) **CLAIM**

We claim the ornamental design for a bottle, as shown and described.

DESCRIPTION

FIG. 1 is a perspective view of a bottle showing our new design;

FIG. 2 is a front elevation view thereof;

FIG. 3 is a side elevation view thereof; and,

FIG. 4 is a top plan view thereof.

The cross line pattern represents surface shading.

The broken-line disclosure in the view is for illustrative purposes only and forms no part of the claimed design.
